UNITED STATES PATENT OFFICE.

HARRY B. FARRAND, OF PHILADELPHIA, PENNSYLVANIA.

CONTINUOUS ROTARY ELECTROPLATING MACHINE.

Application filed June 27, 1923. Serial No. 647,983.

To all whom it may concern:

Be it known that I, HARRY B. FARRAND, a citizen of the United States, residing at 4722 North Franklin Street, Philadelphia, 5 in the county of Philadelphia and State of Pennsylvania, have invented new and useful Improvements in Continuous Rotary Electroplating Machines, of which the following is a specification.

10 My invention relates to continuous rotary electroplating machines, and has for its object to so construct such a machine as to provide for the continuous feeding of the articles to be plated by a rotary barrel in which 15 said articles will be progressively moved rearward while being subjected to the plating process, and when the plating process is completed said articles will be delivered to a shoot or receptacle from which they will be 20 elevated and conveyed to the point of delivery.

A further object of my invention is to subject the articles being plated to the flow 25 of plating currents from opposite directions so as to effect plating upon opposite sides of the articles simultaneously.

With these and other ends in view, this invention consists in the details of construction and combination of elements herein- 30 after set forth and then specifically designated by the claims.

In order that those skilled in the art to which this invention appertains, may understand how to make and use the same, I will 35 describe its construction in detail, referring by numerals to the accompanying drawings forming a part of this application, in which;—

Fig. 1, is a plan view of a plating apparatus made in accordance with my improvements, a portion of the barrel being broken away to show the interior thereof.

Fig. 2, is an elevation one side of the vat being removed and a portion of the mechanism broken away and sectioned.

Fig. 3, is a section at the line 3—3 of Fig. 1 looking in the direction of the arrow.

Fig. 4, is a detail view of the internal anode.

50 In carrying out my invention as here embodied 1 represents a vat or tank for containing the plating solution and crosswise of this tank are secured the supporting beams 2 and 3 arranged in pairs and upon 55 these beams are mounted the bearings 4 in which are journalled the rolls 5.

6 represents the rotary barrel or cylinder having a flange 7 at each end thereof, and this barrel is supported upon the rolls 5 in such manner that the flanges 7 project between the beams 2 as clearly shown in Fig. 2 thus preventing any longitudinal movement of the barrel. 60

In order that power may be applied to the barrel for revolving the same a worm wheel 65 8 is secured upon its periphery and with this worm wheel meshes the worm 9 the latter being mounted upon the shaft 10 which is journalled in the bearings 11, and has a pulley 12 secured upon one end thereof by 70 which the worm may be revolved through the medium of a belt applied to said pulley.

The interior of the barrel is provided with a spiral rib 13, and the walls of this barrel are perforated as indicated at 14 in 75 order that the plating solution may have free circulation through and within the barrel.

15 represents a hopper in which the articles to be fed to the barrel are placed and 80 from which said articles pass downward through the opening 16 between the sliding board 17 and the deflecting partition 18 and reach the pocket 19 from which they are elevated by the carrier belt 20 running over 85 the pulleys 21 and 22.

As the articles fall from the carrier belt 20 as the latter passes around the pulley 22 they will be guided into the front end of the barrel, and as the latter revolves these 90 articles will be successively carried rearward by the action of the rib 13 until they finally fall from the rear end of the barrel into the pocket 24 from which they will be elevated by the conveyer belt 25 running over the 95 pulleys 26 and 27, being thus delivered to the point outside of the vat as will be readily understood.

28 represents two rods extending lengthwise of the vat and suitably supported thereby from which may be suspended the anodes 100 29 by means of the hooks 30 carried by said anodes and if desired the lower end of these anodes may be supported in any suitable manner. 105

A rod 31 extends through the barrel and is supported at each end in suitable bearings 32 and from this rod is suspended a series of chains 33 in such manner that the lower portion of said chains will ride upon the 110 inner surface of the barrel as clearly shown in Fig. 3, said chains serving as cathodes.

I also provide a rod 34 which passes through the barrel and is supported in the bearings 35, this rod is utilized for the suspension of the interior anodes 36 said anodes being 5 preferably made in the form of a segment as shown in Fig. 4 and having the suspending wires 37 attached thereto for convenience in suspending these anodes from the rod 34.

10 The rods 28 and 34 are electrically connected with a source of positive current while the rod 31 is connected with the negative.

From the foregoing description the operation 15 of my improved apparatus will be obvious as follows:

The speed of the carrier belt 20 being so timed relative to the rotations of the barrel 20 the small articles to be plated will be delivered in a continuous stream to the barrel and fed lengthwise of said barrel by the spiral rib, in the meantime being constantly stirred and tumbled while the current flowing from the anodes 29 will plate 25 the surfaces exposed in the direction of said anodes and the current flowing from the anodes 36 will plate the opposite exposed surfaces of said articles thus producing the desired thickness of plating in considerably less time than where external anodes 30 are utilized. This plating process will proceed automatically as long as the apparatus is in operation and the articles supplied to the hopper thus lessening the time and labor 35 and producing a better quality of work.

Of course I do not wish to be limited to the exact details of construction as herein shown as these may be varied within the limits of the appended claims without departing 40 from the spirit of my invention.

Having thus fully described my invention, what I claim as new and useful is:—

1. In an apparatus of the character described a vat, a series of rolls mounted within 45 said vat, a perforated barrel supported by said rolls, a rib spirally disposed within the barrel, a worm wheel mounted upon the barrel, a worm meshing with said worm wheel for revolving the latter, a hopper

adapted to receive the articles to be plated, 50 a conveyer for elevating said articles from the hopper; a shoot for conveying the articles from the conveyer to the interior of the barrel; a pocket for receiving the articles from the barrel, a conveyer for elevating the articles from said pocket; a series of anodes disposed adjacent to the barrel upon the outside thereof; a second series of anodes supported within the barrel and out of contact with the latter; and a series 60 of flexible cathodes suspended within the barrel and arranged to lie against the interior surfaces of said barrel; for use in a plating system an internal anode consisting of an arcuate section of plating metal and 65 suspending wires attached to said barrel.

2. An electroplating apparatus comprising a vat, supporting beams arranged in pairs, the beams of each pair being spaced apart, rolls journaled upon said beams, a 70 perforated cylinder mounted upon said rolls, a flange at each end of the cylinder projecting between the beams of each pair to prevent longitudinal movement of the cylinder, a worm wheel on the cylinder intermediate 75 its ends, a worm meshing with the worm gear, means to revolve the worm, a spiral rib within the cylinder, anodes within the vat, and cathodes within the vat inside of the cylinder.

3. An electroplating apparatus comprising a vat, a perforated cylinder rotatably mounted within the vat, a spiral rib within the cylinder, means to rotate said cylinder, a stationary rod passing through the cylinder and adapted to be connected with a source of electric energy, a segmental anode, wires fastened to the anode and engaging the stationary rod to suspend said anode within the cylinder, another rod passing through the cylinder adapted to be connected with a source of electrical energy, and a flexible cathode attached to said last named rod and lying on the interior surface of the cylinder.

In testimony whereof, I have hereunto affixed my signature.

HARRY B. FARRAND.
